UNITED STATES PATENT OFFICE.

JOSEPH A. BUTCHER, OF LAKE CHARLES, LOUISIANA.

ATTACHMENT FOR OIL TANKS.

Application filed May 29, 1926. Serial No. 112,671.

This invention relates to oil tanks generally, more particularly to an attachment therefor for preventing explosions from accumulating gases or vapors within the tank, 5 and is an improvement upon the means for the purpose aforesaid as disclosed in Letters Patent No. 1,811,753, granted to me July 29, 1919, and the invention has for its object to provide, in a manner as hereinafter set forth, means communicating with the outtake pipe of the tank for relieving the latter from gases or vapors generated therein, while the oil is stored in the tank or when filling and emptying the tank or 10 caused from any other source thereby reducing the possibility of explosions within the tank to a minimum, and further for condensing such gases or vapors exteriorly of the tank as well as for collecting the condensates.

Further objects of the invention are to provide, in a manner as hereinafter referred to, an attachment for the purpose set forth, which is comparatively simple in its construction and arrangement, strong, durable, compact, readily installed with respect to one or a plurality of tanks, automatic in its action, and comparatively inexpensive to set up.

With the foregoing and other objects in view, the invention consists of the novel construction, combination and arrangement of parts as hereinafter more specifically described and illustrated in the accompanying drawings wherein is shown an embodiment of the invention, but it is to be understood that changes, variations and modifications can be resorted to, which fall within the scope of the claims hereunto appended.

The drawing illustrates in elevation, an oil tank showing the adaptation therewith of an attachment in accordance with this invention.

Referring to the drawing in detail 1 denotes an oil tank, which may be of any suitable form, but preferably is that disclosed by the aforesaid mentioned Letters Patent, and 2 indicates a suitable inlet pipe or intake which opens into the tank 1 at the bottom thereof. Communicating with the upper portion of the tank 1 is a lateral outlet pipe 3 and which provides means for the discharge of the accumulating gases or vapors generated within the tank 1.

Connected to the outlet pipe 3 is a T-coupling 4 from which extends a discharge

line 5 consisting of a vertically disposed branch 6 which depends from the T-coupling 4 below the bottom of the tank, branches 7, 8, 9 and 10 which extend at 60 right angles with respect to the lower end of the branch 6, a vertically disposed stand pipe 11, a coupling or housing 12 arranged at the top of the stand pipe 11 and provided with an outlet 13, a cut-off valve 14 interposed between the branches 7 and 8, a T-coupling 15 interposed between the branches 8 and 9, a four-way coupling 16 interposed between the branches 9 and 10, and an elbow coupling 17 is interposed between the branch 10 and the lower end of the stand pipe 11. Extending from the outer end of the T-coupling 4 is a combined vent and overflow line 18 which consists of a pair of pipe branches 19, 20, 65 a check valve 21 connecting the branches 19 and 20 together, a vertically disposed pipe branch 22 which opens at its lower end into the T-coupling 15 and has its upper end connected with the pipe branch 20 by 70 an elbow coupling 23. The branch 19 opens into the T-coupling 4 and said branch 19, check valve 21 and branch 20 is disposed at right angles with respect to the upper end of the branch 6 of the discharge line 5.

Arranged below the elbow coupling 17 is a tank 24 which provides a collector for the condensates and a pipe 25 leads from the top of the tank 24 and opens into the elbow coupling 17 whereby communication is 75 established between the discharge line 5 and the tank 24. The tank 24 has extending therein a discharge pipe 26 for the condensates and said pipe 26 depends into the tank 24 to a point in proximity to the bottom thereof. The tank 24 has also connected therewith a normally closed valve controlled pressure supply pipe 25, and the latter when opened provides means for supplying air under pressure to the tank 24 for the purpose of forcing the condensates up through the discharge pipe 26 from the tank. The valve casing or coupling 12 is provided with a safety valve 27. Attached to the four-way coupling 16 is a plurality of discharge lines 28 which lead from other oil storage tanks and the attachment can be employed in the manner where one stand pipe and one collecting tank 24 can be used for a plurality of oil storage tanks.

If the valve 14 is closed the tank 1 can be vented, or the accumulated gases or

vapors conducted therefrom through the medium of the line 18 which leads from the tank 1 and opens into the discharge line 5 rearwardly of the valve 14. The line 18 acts as a vent for the tank 1 when filling or emptying the tank. The accumulating gases or vapors can pass out through the line 5 and also through the line 18 and on the travel thereof they will come in contact with the air in the line 5 and the gases or vapors are condensed and the condensates fall into the tank 24 from which they can be discharged when desired.

The valve 14 can be closed to cut off ignited or burning oil in event of the same taking fire and the tank vented through the line 18 of the gases or vapors or products of combustion. When the tank is being filled with oil the valve 14 is closed and the tank is vented through the line 22. When filling the tank the overflow is conducted off by the line 22 which opens into the line 5 by way of the valve 14.

It is thought that the many advantages of an attachment for the purpose referred to and in accordance with this invention can be readily understood and although the preferred embodiment of the invention is as illustrated and described, yet it is to be understood that changes in the details of construction can be had which will fall within the scope of the invention as claimed.

What I claim is:

1. An attachment for oil storage tanks comprising a gas accumulating discharge line leading from the upper portion of the tank and including a vertically disposed branch depending below the bottom of the tank and an angularly disposed branch positioned below the bottom of the tank and terminating in a vertically disposed stand

pipe having a safety valve at its upper end, a cut-off arranged in said angularly disposed branch intermediate the ends thereof, a valve controlled vent line leading from a point in proximity to the tank and opening into said discharge line forwardly of said cut-off, and a condensate collector communicating at its top with said discharge line forwardly of said cut-off, and means for discharging the condensates from said collector.

2. An attachment for oil storage tanks constructed in accordance with claim 1, said angularly disposed branch provided with means for coupling a plurality of discharge lines therewith.

3. An attachment for oil storage tanks comprising a discharge line for accumulated gases, said line leading from the upper portion of the tank and including a vertically disposed branch depending below the bottom of the tank and angularly disposed branch extending from and positioned below the bottom of the tank, a vertically disposed stand pipe having its lower end communicating with the forward end of said angularly disposed branch provided at its top with a safety valve, a cut-off in said angularly disposed branch intermediate the ends thereof, a condensate collector communicating at its top with the forward end of said angularly disposed branch, means for discharging the condensates from said collector, and means interposed in said angularly disposed branch forwardly of said cut-off for coupling therewith a plurality of discharge lines.

In testimony whereof, I affix my signature hereto.

JOSEPH A. BUTCHER.
